SEALED CONTACT DEVICE

Bruno Dal Bianco, Milan, and Mario Scata, Monza, Italy, assignors to International Standard Electric Corporation, New York, N.Y., a corporation of Delaware

Filed Apr. 28, 1960, Ser. No. 25,437

Claims priority, application Italy June 17, 1959

5 Claims. (Cl. 200—87)

This invention relates to electromagnetically or magnetically operated make and break electrical contact devices, and particularly to make and break contacts of the type enclosed in a protective vessel in which the mechanical elements, subjected to a magnetic field, are used also as members conveying the current to the contact points.

Devices of this kind generally comprise a small glass tube, at the ends of which are sealed magnetic material wires or small bars. The tube is either air evacuated or filled with an inert gas. In these prior-art devices, the ends of the two magnetic wires inside the glass tube are overlapped with a small air gap therebetween. The tube is generally put inside an electromagnetic coil which, when current flows through its winding, causes the two wires to contact each other, closing an external electric circuit connected thereto.

One of the features of the present invention is to provide an improved device of the type described which gives economical advantages and simplicity in fabrication, is easy to put into operation and designed to be used for various purposes depending upon the number of contact elements placed inside the vessel.

A further object of the invention is the production of a strong device of very small size, easy to be replaced, and which is based on the principles disclosed in our copending U.S. patent application No. 722,194, filed March 18, 1958.

One of the main objects of the invention is the fabrication of a control device for electrical circuits, which is not integral with the energizing coil and which has, in most cases, the magnetic structure sealed to the container by one end only permitting easy assembly on printed circuits.

A further feature of the invention is that, in the manufacture and adjustment of the mechanical structure of the device, all pieces are worked outside the protective vessel, and then sealed thereto by automatic means requiring no particular arrangement or jig to adjust the contact gap, the latter being adjusted when the structure touches the closed end of the container before the sealing operation.

Another object of the invention is to provide a switch structure which, by slight variations, can be modified from a simple circuit maker and breaker to a multi contact changeover switch.

A short description will now be given for the better understanding of the scope of the present invention as illustrated in the various embodiments shown in the accompanying drawings, in which:

FIG. 1 shows, on an enlarged scale, a sectional view of the switching unit of the inventive switch structure.

FIG. 2 shows a complete switch structure comprising the switching unit of FIG. 1 and an associated flux generating core and winding.

FIG. 3 illustrates, a sectional view of the switching unit of FIG. 1, modified to provide a multi-contact changeover relay.

FIG. 4 illustrates, on an enlarged scale, an alternative of the contact structure in which the armature is formed by a disc free to rotate about its guiding axis.

FIG. 5 shows, on an enlarged scale, a section view of

2

the contact device of FIG. 4 in which two electrodes are added to provide a sequence of switching operations.

FIG. 6 shows, on an enlarged scale, a sectional view of a further arrangement of the movable armature inside the vessel.

5 FIG. 7 shows an end sectional view of the device illustrated in FIG. 6, to show the operation of the movable armature of the device.

The sealed electric contact device of FIG. 1 comprises a small vessel 1, generally of glass and of cylindrical shape, the size of which could be 5 x 10 mm. At one end of the vessel there are sealed the electrical contact elements, forming a magnetic structure which comprises a U-shaped thick wire 2. On two ends 3 and 4 of the U-shaped wire 2, a third piece of wire 5 of very good magnetic material is bridged across. The bridge piece or armature is electrically connected to one of the arms 3 or 4 of the U-shaped wire 2 by means, for example, of a flat spring 6, welded near the end of arm 3 and to one end of the bridge piece 5. Spring 6 urges armature 5 away from arm 4. Upon the introduction of the magnetic structure into the vessel, spring 6 is loaded when the top of the structure touches the bottom of vessel 1, to obtain the wanted gap between the open contacts of the relay. 10 After sealing the arms 3—4 to end 7 of vessel 1, the base of the U-shaped wire 2, which is generally larger than the separation of the branches sealed into the vessel, is cut along the line a—a, and the device is now ready to be connected to the circuit of FIG. 2.

15 It is evident that the bridge piece 5 and its supporting seats could be made with various shapes other than the flat one without thereby affecting the operational conditions of the magnetic structure.

20 The ends of bridge piece 5 in contact with the ends 3—4 of the U bar could be coated with a suitable metal of good electrical conductivity.

25 FIG. 2 illustrates schematically the way in which to insert the sealed contact device into the energizing structure. The magnetic contact carrier structure or switching unit, after the U base cutting, will provide two terminal lugs 8 and 9 which, when inserted between pole pieces N—S of an open magnetic circuit M, will complete a magnetic circuit through the movable armature 5 enclosed in vessel 1. The main advantage of this arrangement is that the length of the mean turn of the energizing coil 10 is brought to a minimum depending only upon the diameter of the core forming the magnetic circuit M. This provides advantages from the point of view of the magnetic force obtainable and for the small size of the energizing coil.

30 This arrangement also permits a great number of applications and an easy replacement possibility of the contact structure.

35 In FIG. 3 there is illustrated the contact device of FIG. 1 suitable to perform a switching of electrical circuits. In this case bridge piece 5 through the effect of spring 6 is strongly pressed against the stationary contact 11, sealed to the other end of vessel 1.

40 The adjustment of the gap between the end of bridge piece 5 and the top of bar 4 is made as soon as the magnetic structure is put into the vessel 1, before arms 3—4 are sealed to the container.

45 In FIG. 4 there is illustrated a constructional alternative of FIG. 1 in which bridge piece 5 is replaced by a disc 12 of magnetic material of good property. The disc 12 is kept by a spindle 13, L-shaped or by other means soldered to one of the arms 3 or 4. The disc 12 is free to rotate on said spindle 13 and is urged upwards by a cylindrical spring 14. A stop 15 prevents the disk from leaving axis 13.

50 It will be understood that by this arrangement the face of the disc which comes in contact with the ends

of bars 3—4 continually changes its own position with respect to these bars, for each attraction, with considerable advantages when closing the circuit connected to bars 3—4.

In FIG. 5 there is illustrated the same arrangement of FIG. 4 modified to obtain a changeover switch. In this case disc 12 has both faces adapted to make a very good electrical contact when urged against the top of the rods of another U-shaped piece 16 of non-magnetic material, sealed to the other end of vessel 1 and when attracted against the ends of bars 3—4, to make a work contact.

In FIGS. 6 and 7 there is illustrated a further shape which can be given to the sealed contact elements of the relay.

As seen in the side view of the vessel shown in FIG. 6, an extension 17 of a leaf 18 of very good magnetic material is mechanically and electrically secured to one of the arms 3 or 4.

Leaf 18, as seen in the end view of FIG. 7, while having one of its sides in close contact with arm 3, has the other side slightly spaced from arm 4. The surfaces which come in contact between arm 4 and one side of the leaf 18 are provided with coatings of metal of good electrical conductivity. It must be noted that due to the cylindrical form of container 1, leaf 18 will find a natural rest position over the internal wall of the glass tube which will define the rest position of leaf 18.

From the foregoing it will be clear that the novel form given to the contact device in the various examples previously illustrated, will permit a number of applications especially in the switching field, it being possible to embody switches and multiswitches for step-by-step and crossbar systems.

It is to be understood that the devices described above are examples embodying the principles of the present invention. A number of other devices could be designed by those skilled in the art without departing, however, from the spirit and the scope of the present invention.

What is claimed is:

1. A magnetically operated switch structure comprising a switching unit having first and second spaced parallel bars of magnetic material and a co-operating armature of magnetic material positioned in flux-linking relationship therewith, means for electrically connecting one end of said armature to said first bar and for sup-

porting the other end of said armature for movement to selectively make and break an electrical connection between said armature and said second bar, the said supporting means urging the said armature away from 5 said second bar, an enclosing envelope within which said armature and a portion of said bars are enclosed with the other portion of said bars extending externally out of one end of said envelope and sealed therethrough in a vacuum-tight manner and with the said armature being positioned with respect to the other end of said envelope to abut thereagainst when the switch is in an unoperated state to provide a desired air gap between the said armature and said second bar, and a magnetic flux generating unit comprising an open-ended core having a flux-generating winding thereon with the ends of 10 said core in flux-linking relationship with the said external portions of said bars.

2. A magnetically operated switch structure as set forth in claim 1 wherein the said means for movably 20 supporting said armature includes means for positioning the said armature substantially at right angles to the longitudinal axis of said pair of bars.

3. A magnetically operated switch structure as set forth in claim 1 wherein the magnetic material in said 25 pair of bars and said armature is non-flexible.

4. A magnetically-operated switch structure as set forth in claim 1 wherein the said abutting portion of the 30 said envelope includes an electrical conductor normally in electrical contact with said armature and the said first bar of said pair of bars.

5. A magnetically operated switch structure as set forth in claim 1 wherein the cross-sectional area of said 35 core is less than the cross-sectional area of said envelope.
